TAPE CARTON

Filed Sept. 8, 1936

UNITED STATES PATENT OFFICE

2,101,355

TAPE CARTON

Charles E. Wonder, Chicago, Ill., assignor to Van Cleef Bros., Chicago, Ill., a partnership composed of Noah Van Cleef, Maxime Van Cleef, Felix Van Cleef, and Paul Van Cleef

Application September 8, 1936, Serial No. 99,703

2 Claims. (Cl. 206—52)

The present invention relates generally to cartons. More particularly the invention relates to that type of carton which is formed from a one-piece blank of cardboard and consists of a pair of laterally spaced sides, a pair of end walls, and a bottom and top and is designed to hold and encase a roll of tape or like article having a ring-shaped core or central aperture.

One object of the invention is to provide a carton of this type which includes simple and improved means for centering the roll of tape with respect to the side walls and top and bottom in order to prevent injury or damage to the outer convolutions of the tape in the event that the carton is dropped or struck.

Another object of the invention is to provide a container of the type under consideration in which the centering means for the roll of tape comprises an annular series of tongues which are formed in the central portion of one of the sides of the carton by way of a central hole and a plurality of equidistantly spaced, radially extending, tongue defining slits and are designed after insertion of the roll of tape into the carton to be bent inwardly into a position wherein they extend at substantially right angles to the side to which they are attached and engage the inner periphery of, and form a centering band for, the core of the roll.

A further object of the invention is to provide a carton of the last mentioned character in which the means for centering the roll of tape with respect to the side walls and top and bottom comprises in addition to the annular series of tongues a cardboard ring which is adapted after inward bending or folding of the tongues into engagement with the inner periphery of the core of the roll to be inserted within the tongues into a position wherein it serves to hold the tongues in their band forming position within the core of the roll.

A still further object of the invention is to provide a carton of the type and character under consideration in which the top is formed as an integral part of, and is foldable with respect to the other side wall to form a closure for the carton and embodies an integral flap which is adapted to be folded across the tongue-equipped side wall and serves when in its folded position to hold the ring against displacement from its operative position within the tongues.

An additional object of the invention is to provide a roll holding carton which is generally of new and improved construction and may be manufactured at a low and reasonable cost.

Other objects of the invention and the various advantages and characteristics of the present roll holding or retaining carton will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective of a carton embodying the invention;

Figure 2 is a perspective view showing the tongues before they are bent inwards into engagement or interlocking relation with the core of the roll;

Figure 3 is a perspective of the ring for holding the tongues in their operative position;

Figure 4 is a sectional view illustrating the general construction and design of the carton and showing the tongues before inward bending thereof; and

Figure 5 is another sectional view showing the container with a roll of tape therein and the tongues and ring in their operative position wherein they serve to center the roll with respect to the side walls and top and bottom of the carton.

The carton which is shown in the drawing constitutes the preferred embodiment of the invention. It is adapted primarily to hold and encase a roll of tape T and is formed of a one-piece blank of cardboard. The tape T is shown as being wound or rolled into spiral form on a ring-shaped core C. The carton consists of a pair of sides 6 and 7, a pair of end walls 8 and 9, a bottom 10, and a top 11 and as hereinafter described, embodies means for centering the roll of tape with respect to the side walls and top and bottom in order to prevent injury or damage to the outer convolutions of the tape in the event that the carton is dropped or struck. The sides 6 and 7 are square, as shown in the drawing. They are positioned in laterally spaced relation and together with the end walls 8 and 9 and the bottom 10 and top 11 form a compartment 12 for the roll of tape T. The end walls 8 and 9 extend between and serve to space apart the side walls of the carton and embody in-turned tabs 13 at the upper margins thereof, and in-turned tabs 14 at their lower margins. The tabs 13 are formed as integral parts of the end walls 8 and 9 and are adapted to

fit between the upper margins of the sides and underlie the end portions of the top 11 when the carton is in its closed position. The tabs 14 are also formed as integral parts of the end walls 5 of the carton and are bent or folded inwards so that they fit between the bottom margins of the carton sides and overlie the end portions of the bottom 13 when the carton is fully assembled, that is, in its closed position. The end wall 8 is 10 formed integrally with the adjoining or contiguous end margins of the carton sides and forms a connection between the side 6 and the side 7. The end wall 9 is joined at one side margin thereof to the contiguous or adjoining side margin of the side 7 and is connected at the other side margin thereof to the contiguous side margin of the side 6 by a flap 15. The latter extends at right angles to and is formed integrally with the side 6 and fits against and is cemented or otherwise fixedly secured to the inner face of the end wall 9. The bottom 10 is joined to and extends at right angles to the bottom margin of the side 7 and embodies an inturned flap 16 along its outer margin. This flap is adapted to be inserted between the tabs 14 and the bottom margin of the side 6 and serves to secure the bottom in its closed position. The top 11 is joined to the top margin of the side 7 and is adapted to be folded inwardly over the tabs 13 so as to close the compartment 30 12 after insertion of the roll of tape T.

The means for centering the roll of tape T with respect to the side walls 6 and 7 in order to prevent injury or damage to the outer convolutions in the event that the carton is dropped 35 or struck consists of an annular series of tongues 17 and a ring 18. The tongues 17 are formed in the central portion of the side 6 and are adapted to be bent inwardly into a position wherein they extend across the compartment 12 and form 40 a centering band for the core C of the roll of tape T. They are substantially in the form of equilateral triangles and are formed by a central hole 19 and equidistantly spaced slits 20 in the central portion of the carton side 6. The 45 slits 20 extend radially from the hole 19 with the result that the tongues 17 are free along the inner ends and side edges thereof and are connected to the side 6 at their outer ends. Straight scores 21 are preferably formed in the 50 side 6 between the outer ends of the slits 20 so as to facilitate inward bending of the tongues 17. In view of the fact that the scores are straight the band which is formed by the tongues when the latter are in their operative position 55 within the core C of the roll of tape T is polygonal as far as peripheral conformation is concerned. Preferably the flaps 17 are formed so that the band which is formed by them when they are in their operative position is substantially 60 the same in diameter as the inner periphery of the core C so that the roll of tape T is held against lateral displacement in the compartment 12 as well as centered. As shown in Figures 4 and 5, the tongues 17 are of such 65 length that they extend substantially from the side 6 to the side 7 when they are in their band forming position. Prior to insertion of the roll of tape T into the compartment 12 the tongues 17 are retained in a position where they are substantially 70 flush with the side 6. After insertion of the roll of tape into the compartment the tongues are bent inwardly into their band forming position wherein they engage the inner periphery of the core C. The ring 18 serves 75 to retain the tongues within the core. It is

formed of cardboard or like material and is adapted to be inserted through the central part of the side 6 into a position wherein it fits within the tongue formed band and serves to urge the tongues outwards into engagement with the inner periphery of the core C. The height of the ring 18 is substantially equal to the distance between the carton sides 6 and 7 and the diameter of the ring and is slightly greater than the diameter of the tongue formed band. By 10 having the ring of slightly greater diameter than the tongue formed band the tongues are urged inwards into firm contact with the core C when the ring is in place, and the ring itself as the result of its frictional contact with the scored portions of the central part of the carton side 6 is held against axial displacement with respect to the carton. In order additionally to hold the ring 18 in place within the tongue formed band, the top 11 is provided with an 15 integral flap 22. This flap is joined to and is foldable with respect to the outer side margin of the top and is the same in size as the side 6. It is adapted when the top 11 is in its closed position to overlie the carton side 6 and embodies 20 at the distal margin thereof an extension 23 and a tab 24 for securing it in place. The extension 23 is formed integrally with and is bendable relatively to the flap 22 and is similar 25 in size to the bottom 10 of the carton. When 30 the flap 22 is in place the extension 23 is adapted to fit against and underlie the carton bottom 10 (see dotted line position of extension in Figure 5). The tab 24 is of restricted or limited 35 length and is hinged to the central portion of the outer side margin of the extension 23. It is bendable or foldable relatively to the extension and is adapted to extend through a slot 25 into a position wherein it is disposed 40 between the bottom portion of the side 7 and the roll of tape T. The slot 25 is formed in and extends longitudinally of the carton bottom 10 and is located adjacent to the point where the bottom is joined to the bottom margin of the carton side 7. When the tab 24 is in its operative 45 position, that is, when it extends through the slot 25 into the compartment 12, the top 11, the flap 22 and the extension 23 are respectively held in place against the tabs 13, the side 6 and the carton bottom 10. 50

In assembling or mounting the roll of tape T in the carton, the top 11 and the flap 22 are first swung into their open position (see Figure 4). Thereafter the tabs 13 are swung outwardly so as to permit of complete access to 55 the compartment 12 and the roll of tape T is slid into the compartment into a position wherein in the core C is aligned or coaxially positioned with respect to the hole 19. After the roll of tape is so positioned the tongues 17 are folded 60 inwards until they engage and form a band around the inner periphery of the core C. After inward folding of the tongues the ring 18 is inserted within the tongue-formed band so that it serves to prevent the tongues from swinging 65 outwards out of locking relation with respect to the core. After insertion of the ring within the tongue formed band the tabs 11 are folded inwards and the top 11 is folded or swung into its closed position. Thereafter the flap 22 is swung 70 into lapped relation with the side 6 of the carton and the tab 24 is inserted into the slot 25 and pushed or forced inwardly until the extension 23 abuts against or underlies the carton bottom 10. When the flaps 23 and the ring 18 are 75

in their operative position the roll of tape T is centered within the compartment 12 and is held against sidewise displacement with the result that the outer convolutions are not likely to be injured or damaged in the event that the carton is dropped or struck. The flap 22 when in lapped relation with the side 6 holds in place the ring 18 which in turn holds the flaps 17 in band form within the core C of the roll of tape T. When it is desired to remove the tape T from the container it is only necessary to swing the flap 22 and top 11 into their open position and then remove the ring 18 and swing outwardly the tongue 17.

15 The herein described carton is simple as far as construction is concerned and may be manufactured at a low and reasonable cost.

Whereas the carton has been described for use primarily with a roll of tape T having a core 20 C, it is to be understood that the carton may be used to hold other articles having central apertures. It is also to be understood that the invention is not to be restricted to the details set forth, since these may be modified within the 25 scope of the appended claims, without departing from the spirit and scope of the invention.

Having thus described the invention, what I claim as new and desire to secure by Letters Patent is:

30 1. A carton for retaining and holding a roll of tape or like article, comprising a side having a central opening therein, a second side positioned opposite and in spaced relation to the first mentioned side, end walls extending between the end 35 margins of the sides, a top and bottom extending respectively between the top and bottom margins of the sides and forming with the sides and

the end walls a compartment for the roll, an annular series of tongues connected to and extending inwardly from the opening defining margin of said first mentioned side and serving to form a centering band within the core of the roll, a removable ring extending through said opening and within the tongues and arranged to hold the tongues in their band forming position, and a flap hinged to the top and adapted to be swung into a position wherein it overlies said first mentioned side and operates to hold the ring against axial displacement. 5 10

2. A carton for retaining and holding a roll of tape or like article, comprising a side having a central opening therein, a second side positioned 15 opposite and in spaced relation to the first mentioned side, end walls extending between the end margins of the sides, a bottom extending between the bottom margin of the sides and having a slot therein, a top hinged to the top margin 20 of the second mentioned side and adapted to form a closure for the carton, an annular series of tongues connected to and extending inwardly from the opening defining margin of said first mentioned side and serving to form a centering 25 band within the core of the roll, a removable ring extending through said opening and within the tongues and arranged to hold the tongues in their band forming position, and a flap on the top adapted when the top is in its closed position to lap said first mentioned side and hold the ring against axial displacement and having a tab at its distal end adapted to fit within the slot in the bottom in order releasably to hold it in place. 30 35
